[57] CLAIM

The ornamental design for an scrubbing element for attachment to the palm or finger surfaces of an elastic glove, as shown.

DESCRIPTION

FIG. 1 is a top plan view of an scrubbing element for attachment to palm or finger surfaces of an elastic glove showing our new design;

FIG. 2 is an end elevational view thereof, as viewed from the right end thereof;

FIG. 3 is a sectional view thereof, taken along line 3—3 thereof; and

FIG. 4 is a bottom plan view thereof.

FIG. 1**FIG. 2****FIG. 3****FIG. 4**
